[57] CLAIM

The ornamental design for a cabinet, as shown and
described.

DESCRIPTION

FIG. 1 is a front perspective view of a cabinet showing
my new design;

FIG. 2 is a left side elevational view, the right side being
a mirror image thereof;

FIG. 3 is a front perspective view in an open condition;
and

FIG. 4 is an enlarged sectional view taken through
the lower portion of one of the front doors and disclosing
the molding features thereof in greater detail.

The rear surface is conventionally flat and unornamented.

FIG. 1

FIG. 2

FIG. 3

FIG. 4
